UNITED STATES PATENT OFFICE.

EDDIE O. WEST, OF STAFFORD, KANSAS.

DISPLAY CASE.

Application filed April 14, 1925. Serial No. 23,009.

This invention relates to improvements in store furniture, and is more particularly adapted to a case or cabinet for displaying merchandise in a neat and sanitary manner.

5 One of the important objects of the present invention is to provide a display case of the above mentioned character which includes a box or bin in which the merchandise to be displayed is placed, the box being normally disposed at an angle, means being provided for facilitating the outward movement of the box from the cabinet simultaneous with the opening of the closure arranged at the rear of the cabinet.

10 15 A further object of the invention is to provide a display case of the above mentioned character, wherein a tray is hingedly connected at its rear end to the inner side of the closure provided for the cabinet, the tray being adapted to support the box in which the merchandise is contained in the cabinet, at an angle when the closure is in a closed condition, said tray permitting the box to be moved outwardly from the cabinet, 20 25 when the closure is swung to an open position, and further enabling the box to be disposed in a substantially horizontal position, whereby access thereto may be easily had.

30 35 A still further object is to provide a display case of the above mentioned character, which is simple in construction, inexpensive, strong and durable, and further well adapted for the purpose for which it is designated.

40 45 Other objects and advantages of this invention will become apparent during the course of the following detailed description.

In the accompanying drawing forming a part of this specification, and in which like numerals indicate like parts throughout the several views:

Figure 1 is a top plan view of the display case, embodying my invention, and

Figure 2 is a sectional view, through one of the compartments.

50 55 In the drawing, wherein for the purpose of illustration is shown the preferred embodiment of the invention, the numeral 1 designates generally the display cabinet or case, the same comprising the bottom 2, the side 3, the front 4 and the inclined top 5. A vertical partition is arranged intermediate the ends of the cabinet and is arranged transversely therein to provide a pair of compartments, each of which is open at the rear of the cabinet. The top 5 of the cabi-

net is provided with the transparencies 6 for each of the compartments, as clearly illustrated in Figure 1. A closure 7 is provided for the open rear end of each of the compartments, the same being hinged at its lower end as clearly illustrated at 8 in Figure 2. A suitable handle 9 is provided for facilitating the opening and closing of each closure. A pair of longitudinally extending wooden strips 10 and 11 are arranged in the bottom of the cabinet adjacent the front and rear thereof respectively. A pair of spaced rods 12 extend longitudinally in each of the compartments, the forward ends of 60 65 the rods being disposed in the front strip 10, while the opposite ends of the rods are disposed in the rear strip 11. The purpose of the guide rods will hereinafter be more fully described. 70 75

80 85 A tray 13 is arranged in each of the compartments, the same being hingedly secured at its rear end to the intermediate portion of the respective closure 7 in the manner as illustrated at 14. The forward end of each tray is provided with an upstanding flange 14 and the same normally rests on the spaced guide rod 12 at a point adjacent the flat strip 10. The box or receptacle in which the merchandise to be displayed is contained, is 85 illustrated at 16, and the box is supported on the tray 13, in the manner as clearly illustrated in Figure 2. The box is open at its top and when the same is disposed to its respective compartment, the merchandise 90 will be displayed and may be readily seen through the transparency 6 provided in the top 5 of the cabinet, the box being supported at an incline with the tray and is normally in the position shown in Figure 2 95 of the drawing. The upstanding flange 15 formed on the forward end of the tray 13 engages the front end of the box and prevents the displacement of the latter from the tray. 100

105 110 As is obvious from the construction illustrated in the drawing, the merchandise in the boxes contained in the several compartments of the cabinet is at all times visible to the customer. However, it is impossible for the customer to gain access to the contents of the box from either the front or top of the cabinet. The cabinet may be opened at the rear in the manner to be presently described.

115 Grasping the handle 9 of the closure of the desired compartment, and swinging said

closure outwardly on its pivot 8, the tray 13 will be adapted to slide rearwardly along the guide rods 12 and at the same time cause the rearward sliding movement of the box 16 so that a portion of the box will be moved outwardly from the cabinet. It is also to be understood that as the closure 7 is swung rearwardly and downwardly, the tray and box associated therewith will also become lowered so that the tray and box will be disposed in a substantially horizontal position, whereby it will be unnecessary to hold the closure or support the same, while the contents of the box are being removed therefrom.

After the merchandise has been removed from the box or receptacle, the closure 7 is swung upwardly to a closed position, simultaneously returning the tray and box to their normal positions within the compartments.

The display case or cabinet embodying my invention may be constructed of any suitable material, and I do not wish to limit myself to the particular number of compartments which may be provided.

The simplicity in which the present invention is constructed, enables the several parts to be readily assembled or disassembled, and furthermore the box in which the merchandise is placed may be readily and easily inserted or removed from the supporting tray on which the box is adapted to rest when in the cabinet.

While I have shown the preferred embodiment of my invention, it is to be understood that various changes in the size, shape and arrangement of parts may be resorted to, without departing from the spirit of the invention or the scope of the appended claim.

Having thus described my invention, what I claim is:

A display cabinet comprising a case open at its rear, the top of the case being inclined and provided with a transparency, front and rear strips arranged in the bottom of the case, a closure for the open rear end of the case, said closure being hingedly supported at its lower end, a tray pivotally secured at its rear end to the intermediate portion of said hinged closure, said tray being inclined downwardly toward the front of the case, an upstanding flange formed on the forward end of the tray and adapted to engage the forward end of an open top box for supporting the same on the tray, and normally holding the box in an inclined display position in the case, said tray and said box being adapted to be gradually lowered during the outward downward swinging movement of said closure and simultaneously moving the rear portion of the box and the tray outwardly of the case, and guide rods extending between the front and rear strips and on which the forward end of the tray is adapted to slide.

In testimony whereof I affix my signature.

EDDIE O. WEST.
